UNITED STATES PATENT OFFICE

147,882

DESIGN FOR AN END UNIT FOR FLUORESCENT LIGHTING FIXTURE OR THE LIKE

Samuel Allyn Ward, Chicago, Ill., assignor to Ward Electric Company, Chicago, Ill., a corporation of Illinois

Application September 20, 1946, Serial No. 133,443

Term of patent 14 years

(Cl. D48—23)

To all whom it may concern:

Be it known that I, Samuel Allyn Ward, a citizen of the United States, residing at Chicago, in the county of Cook and State of Illinois, have invented a new, original, and ornamental Design for an End Unit for Fluorescent Lighting Fixture or the like, of which the following is a specification, reference being had to the accompanying drawing, forming part thereof.

In the drawing:

Figure 1 is a front elevational view of an end unit for a fluorescent lighting fixture or the like showing my new design.

Figure 2 is a left side elevational view of the same.

I claim:

The ornamental design for an end unit for fluorescent lighting fixture or the like, as shown.

SAMUEL ALLYN WARD.
